UNITED STATES PATENT OFFICE.

LESTER E. SPRAY, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed October 29, 1926. Serial No. 144,936.

My invention relates to railway signaling, and particularly to signaling for the control of traffic along intersecting tracks.

I will describe one form of apparatus embodying my invention and will then point out the novel features thereof in claims.

In the accompanying drawings, Figs. 1^A and 1^B are views which, when placed end to end in the order named constitute a diagrammatic view showing one form of apparatus embodying my invention.

Referring to the drawings, the reference characters A and B designate two intersecting railway tracks along each of which traffic moves in both directions. The track A is provided with a main track section D—E extending in opposite directions from the point of intersection, and with two approach sections C—D and E—F located at opposite ends respectively of the main section. The track B is provided with a main section X—Y extending in opposite directions from the point of intersection, and with two approach sections W—X and Y—Z located at the opposite ends respectively of the main section X—Y.

Each track section is provided with a track circuit comprising a source of current connected across the rails at one end and a track relay connected across the rails at the other end. As here shown, the source of current for each section is a transformer 3, the secondary of which is connected with the track rails and the primary of which is constantly supplied with alternating current from a source not illustrated in the drawing. The track relay for each section is designated by the reference character R with two exponents corresponding to the two limits of the associated section.

Track A is provided with two signals S^D and S^E located at points D and E respectively, and governing traffic in opposite directions along this track through the section D—E, that is, across the intersection of the two tracks. Track B is similarly provided with two signals S^X and S^Y located at the points X and Y respectively, and governing traffic in opposite directions through the section X—Y, that is, across the intersection of the two tracks. Located in the section D—E is a switch H which is normally set for traffic along the track A, but which may be reversed to permit traffic from a siding Q into the track A or vice versa. When switch H

is reversed, traffic from the track Q into track A is governed by a signal S^D₁, and traffic from track A into the siding Q is governed by a signal S^E₁.

All parts of the apparatus except the track transformers are supplied with current from a pair of line wires K and O, which wires are connected with a generator M.

The signals for track A are provided with a signal repeating relay J^A, the circuit for which is from line wire K through wires 21 and 22, contact 5 on signal S^D, contact 4 on signal S^D₁, wire 23, contact 10 on signal S^E, contact 12 on signal S^E₁, wire 24, winding of relay J^A and wire 25 to line wire O. It will be seen that this relay is closed only when all four of the signals associated with track A are at stop.

The signals associated with track B are provided with a signal repeating relay J^B, the circuit for which is from line wire K, through wires 21 and 22, contact 9 on signal S^X, wire 26, contact 14 on signal S^Y, wire 27, winding of relay J^B and wire 25 to line wire O. It will be seen that relay J^B can be closed only when both of the signals for track B are at stop.

The switch H is provided with a repeating relay R^H, the circuit for which is from line wire K, through wires 21 and 22, normally open contact 20 operated by switch H, wire 28, winding of relay R^H, and wire 25 to line wire O. Contact 20 is closed when switch H is reversed, at which time the repeating relay R^H becomes closed.

Track A is provided with a traffic relay G^A which is normally open. This relay is provided with a circuit which passes from line wire K, through wire 29, back contact 30 of track relay R^C_D, wire 31, winding of relay G^A, wire 32, front contact 33 of relay R^D_E, wire 34, back contact 35 of a relay G^B, and wire 36 to line wire O. It will be seen, therefore, that relay G^A will become closed when a train on track A enters the approach section C—D. This relay will also become closed when a train on track A enters the approach section E—F, the circuit then being from line wire K, through wires 37 and 38, back contact 39 of track relay R^E_F, wires 40, 41, 42 and 43, to the winding of relay G^A and then through the same path as before to the line wire O. Relay G^A is also closed when a train occupies section X—Y of track B, the circuit then being from line wire K, through

wire 44, back contact 45 of track relay R^{X_Y} , wires 46, 42 and 43, to the winding of relay G^A , and then through the same path as before to line wire O. Traffic relay G^A will also be closed when the switch repeating relay R^H is closed, the circuit then being from line wire K, through wires 37 and 47, front contact 48 of relay R^H , wires 41, 42 and 43 to the winding of relay G^A , and then through the same path as before, to line wire O. When relay G^A is closed, it will be kept closed if a train on track B enters the approach section W—X, this being due to a stick circuit for relay G^A which passes from line wire K, through wires 49 and 50, back contact 51 of track relay R^{W_X} , wires 52 and 53, front contact 54 of relay G^A , wires 55 and 43 to the winding of relay G^A , and then through the same path as before to line wire O. Another stick circuit is provided for traffic relay G^A which is closed if a train on track B enters the approach section Y—Z, this stick circuit being from line wire K, through wires 56 and 57, back contact 58 of track relay R^{Y_Z} , wires 59 and 53, front contact 54 of relay G^A , wires 55 and 43, to the winding of relay G^A , and then through the same path as before to line wire O.

It will be noted that each of the circuits for traffic relay G^A includes a back contact 35 of traffic relay G^B and front contact 33 of track relay R^{D_E} . This back contact may be shunted when necessary, by a manually operable time release L^A . When this time release is operated it closes a contact 61, whereupon the circuits for relay G^A pass from the winding of this relay through wire 32, front contact 33 of track relay R^{D_E} , wire 60, contact 61 of time release L^A and wire 62, to line wire O.

Traffic relay G^B is provided with a circuit which is closed when a train on track B enters the approach section W—X, this circuit being from line wire K, through wires 49 and 63, back contact 64 of track relay R^{W_X} , wires 65 and 66, winding of relay G^B , wire 67, front contact 68 of track relay R^{X_Y} , wires 69 and 70, back contact 71 of traffic relay G^A , and wire 72 to line wire O. Traffic relay G^B is also provided with a circuit which becomes closed when a train on track B enters the approach section Y—Z, this circuit being from line wire K, through wires 56 and 73, back contact 74 of track relay R^{Y_Z} , wires 75 and 66 to the winding of relay G^B , and then as before to line wire O. When the main section D—E of main track A is occupied, relay G^B is closed by virtue of a circuit which passes from line wire K, through wire 76, back contact 77 of track relay R^{D_E} , and wire 66 to the winding of relay G^B , and then as before to line wire O. When traffic relay G^B is closed and a train on track A enters the approach section C—D, a stick circuit is closed for relay G^B , which circuit passes from line wire K, through wires 21 and 22, normally closed contact 15 of switch H, wire 78, back contact 79 of track relay R^{C_D} ,

wires 80 and 81, front contact 82 of relay G^B , wire 83, to the winding of relay G^B , and then through the same path as before, to the line wire O. It will be seen that this stick circuit is closed only if switch H is in the normal position. Similarly, when traffic relay G^B is closed and a train on track A enters the approach section E—F, a stick circuit for relay G^B becomes closed, which stick circuit is from line wire K through wires 21 and 22, normally closed switch-operated contact 15, wires 78 and 84, back contact 85 of track relay R^{E_F} , wires 86 and 81, front contact 82 of relay G^B , wire 83 to the winding of relay G^B and then through the same path as before to line wire O.

It will be noted that each of the circuits for traffic relay G^B includes a back contact 71 of traffic relay G^A and front contact 68 of track relay R^{X_Y} . This back contact may be shunted when necessary by a manually operable time release L^B having a normally open contact 88 which becomes closed when the time release is operated. The circuits for relay G^B then pass from the winding of this relay through wire 67, contact 68 of track relay R^{X_Y} , wires 69 and 87, contact 88 of time release L^B and wire 89 to line wire O.

When a train on track A enters approach section C—D, it will clear signal S^D , assuming that there are no other trains in the track sections shown in the drawing. The circuit for this signal is then from line wire K, through wire 90, contact 11 on signal S^E , contact 13 on signal S^E_1 , wire 91, front contact 92 of traffic relay G^A , wire 93, back contact 94 of traffic relay G^B , wires 95 and 96, back contact 97 of track relay R^{C_D} , wires 98 and 99, front contact 100 of track relay R^{D_E} , wire 101, front contact 102 of track relay R^{E_F} , wire 103, front contact 104 of track relay R^{X_Y} , wire 105, front contact 106 of signal repeater J^B , wire 107, normally closed contact 108 of time release L^A , wire 109, normally closed contact 16 on switch H, wire 110, operating mechanism of signal S^D , and wires 111 and 112 to line wire O.

If switch H is reversed, switch repeating relay R^H will be closed, switch-operated contact 16 will be open, and switch-operated contact 19 will be closed. The closing of relay R^H will close a branch around the back contact 97 of track relay R^{C_D} in the circuit just traced, which branch is from wire 95, through wire 113, front contact 114 of relay R^H and wire 115 to wire 99. Furthermore, the circuit instead of including signal S^D will include signal S^D_1 , this portion of the circuit being from wire 109 through switch-operated contact 19, wire 116, the operating mechanism of signal S^D_1 , and wires 117 and 112 to line wire O. It follows that with switch H in the reverse position, signal S^D_1 will be cleared even though track relay R^{C_D} is not opened by a train in section C—D.

When a train on track A enters the ap-

proach section E—F, signal S^E will be cleared if switch H is in the normal position, the circuit for this signal being from line wire K, through wires 21 and 118, contact 7 of signal S^D , contact 6 on signal S^D_1 , wire 119, normally closed contact 120 of time release L^A , wire 121, front contact 122 of traffic relay G^A , wire 123, back contact 124 of traffic relay G^B , wire 125, back contact 126 of track relay R^E_F , wire 127, front contact 128 of track relay R^D_E , wire 129, wire 130, front contact 131 of track relay R^C_D , wire 132, wire 133, front contact 134 of track relay R^X_Y , wire 135, front contact 136 of signal repeater relay J^B , wire 137, normally closed contact 17 of switch H, wire 138, operating mechanism of signal S^E and wire 139 to line wire O. If switch H is reversed, switch repeating relay R^H will be closed and front contact 131 of track relay R^D_D will then be shunted by front contact 143 of relay R^H , the path through the latter contact being from wire 129, through wire 144, front contact 143, and wire 142 to wire 133. Furthermore, switch-operated contact 17 will be open and contact 18 will be closed, so that the signal S^E_1 will be cleared instead of signal S^E , the circuit passing from wire 137, through contact 18, wire 140, operating mechanism of signal S^E_1 , and wires 141 and 139 to line wire O.

The circuit for signal S^X is from line wire K, through wire 145, contact 146 on signal S^Y , wire 147, normally closed contact 148 of time release L^B , wire 149, front contact 150 of traffic relay G^B , wire 151, back contact 152 of traffic relay G^A , wire 153, back contact 154 of track relay R^W_X , wire 155, front contact 156 of track relay R^D_E , wire 157, front contact 158 of track relay R^X_Y , wire 159, front contact 160 of track relay R^Y_Z , wire 161, front contact 162 of signal repeater relay J^A , wire 163, operating mechanism of signal S^X , and wires 164 and 112 to line wire O.

The circuit for signal S^Y is from line wire K, through wires 21 and 22, contact 8 on signal S^X , wire 165, front contact 166 of traffic relay G^B , wire 167, back contact 168 of traffic relay G^A , wire 169, back contact 170 of track relay R^Y_Z , wire 171, front contact 172 of track relay R^D_E , wire 173, front contact 174 of track relay R^W_X , wire 175, front contact 176 of track relay R^X_Y , wire 177, front contact 178 of signal repeater relay J^A , wire 179, normally closed contact 180 of time release L^B , wire 181, operating mechanism of signal S^Y , and wire 182 to line wire O.

The operation of the apparatus is as follows:

Assuming that a train on track A moving toward the right enters the approach section C—D, and that there is no other train in any of the sections shown in the drawing, the opening of track relay R^C_D will close at contact 30 the circuit for traffic relay G^A , which relay will therefore become closed. If switch

H is in the normal position and both of the signals for track B are at stop, as well as the signals at point E on track A, the circuit for signal S^D will be completed at the contacts of relays R^C_D and relay G^A , so that this signal will move to the proceed position. When the train enters section D—E, the opening of track relay R^D_E will open the circuit for signal S^D , so that this signal will return to the stop position. The opening of track relay R^D_E will also open at contact 33 the circuit for relay G^A , so that this relay will again open, and relay G^B will then close because its circuit is completed at the back contact 77 of relay R^D_E and also at back contact 71 of relay G^A . As the train enters section E—F, the opening of track relay R^E_F will close the stick circuit for relay G^B , so that this relay will remain closed and will prevent relay G^A from closing and so will prevent signal S^E from being moved to the clear position in the rear of the receding train.

Assuming now that when the train enters section C—D, there is a train at any point between W and Y proceeding toward the right on track B, relay G^A will remain open until the train on track B starts into section X—Y at which time track relay R^X_Y will open and so signal S^D will not be cleared.

The normal operation during the passage of a train along track B will be understood from the foregoing without detailed explanation. If the train is moving toward the right, relay G^B will close as soon as the train enters section W—X whereupon signal S^X will clear. When the train enters section X—Y, relay G^B will open and relay G^A will close, thereby preventing signal S^Y from clearing when the train occupies section Y—Z. A reverse operation will occur if the train is moving toward the left.

I will assume that while there are no trains in the sections shown in the drawing switch H is reversed. This will cause relay R^H to close, and the closing of relay R^H will in turn cause relay G^A to close. Signal S^D_1 will then move to the clear position to permit a train to pass from the siding Q into the main track A. If, however, the approach section E—F is occupied at the time that switch H is reversed, signal S^D_1 will remain at stop and signal S^E_1 will move to the clear position because its circuit is completed at the back contact of track relay R^E_F , and so the train may proceed from track A into the siding Q.

Relay G^A is preferably a quick-releasing relay and relay G^B a slow-releasing relay. The purpose of this is to prevent the possibility of both of these relays starting to close at the same time if two of the track relays for the approach sections on the two tracks respectively, such as relays R^C_D and R^W_X , should close their back contacts at exactly the same instant. Another reason for the slow-releasing characteristic of relay G^B

is to prevent both relays G^A and G^B from closing at the same time when power is restored to the transmission line $K-O$ after having failed.

5. The purpose of the time releases L^A and L^B is to permit the signals on one track to be set at stop and the signals on the other track to be cleared in the event of an emergency. For example, in case a train on track A 10 should break down while occupying the approach section C-D, it may be desirable to clear the signals on track B to permit train movements on the latter track across the intersection. To do this, time release L^B is 15 operated to reverse the position of its contacts, thereby closing the circuit for traffic relay G^B when a train is on one of the approach sections of track B so that signal S^X or S^Y will move to the clear position according 20 as the train on track B is approaching from the left or the right. These time releases are preferably constructed without the usual latch, thereby permitting each release to be closed quickly and to return to its normal 25 position in a predetermined interval of time. This means that the release L^B , for example, can be quickly operated to put the signals for route A at stop, and then will require a considerable period of time to return the release to such position that one signal 30 or the other for route B can be cleared.

Although I have herein shown and described only one form of apparatus embodying my invention, it is understood that various changes and modifications may be made therein within the scope of the appended claims without departing from the spirit and scope of my invention.

Having thus described my invention, what 40 I claim is:

1. In combination, two intersecting railway tracks, a normally open traffic relay for each track, means operating when a train approaches the intersection on either track to close the associated traffic relay, means for preventing either traffic relay from closing if the other traffic relay is closed, a stick circuit for each traffic relay closed when the relay is closed and a train on the other track 50 is approaching the intersection, and signals for said tracks controlled by said traffic relays.

2. In combination, two intersecting railway tracks, a normally open traffic relay for each track, means operating when a train approaches the intersection on either track to close the associated traffic relay, means for preventing either traffic relay from closing if the other traffic relay is closed, a manually operable slow acting device for each relay for permitting the relay to close when the other relay is closed, and signals for said tracks controlled by said relays.

3. In combination, two intersecting railway 65 tracks, a normally open traffic relay for each

track, means operating when a train approaches the intersection on either track to close the associated traffic relay, means for preventing either traffic relay from closing if the other traffic relay is closed, two signals for each track for governing traffic in opposite directions on said track across the intersection, and means for clearing each signal when a train approaches the signal provided the traffic relay for the track occupied by the train is closed and the traffic relay for the other track is open.

4. In combination, two intersecting railway tracks, a normally open traffic relay for each track, means operating when a train approaches the intersection on either track to close the associated traffic relay, means for preventing either traffic relay from closing if the other traffic relay is closed, two signals for each track for governing traffic in opposite directions on said track across the intersection, and means for clearing each signal when a train approaches the signal provided the traffic relay for the track occupied by the train is closed and the traffic relay for the other track is open, and the two signals for the said other track are at stop.

5. In combination, two intersecting railway tracks, a normally open traffic relay for each track, means operating when a train approaches the intersection on either track to close the associated traffic relay, means for preventing either traffic relay from closing if the other traffic relay is closed, two signals for each track for governing traffic in opposite directions on said track across the intersection, and means for clearing each signal when a train approaches the signal provided the traffic relay for the track occupied by the train is closed and the traffic relay for the other track is open, and the track occupied by the train is clear to a point beyond the intersection.

6. In combination, two intersecting railway tracks, a main section for each track extending in opposite directions from the point of intersection, an approach section for each track at each end of the main section, a normally open traffic relay for each track, means operating when a train moving toward the intersection enters an approach section to close the associated traffic relay provided the other traffic relay is open, and signals for said tracks controlled by said traffic relays.

7. In combination, two intersecting railway tracks, a main section for each track extending in opposite directions from the point of intersection, an approach section for each track at each end of the main section, a normally open traffic relay for each track, means operating when a train moving toward the intersection enters an approach section to close the associated traffic relay provided the other traffic relay is open, a stick circuit for each traffic relay closed when the relay is

closed and a train on the other track enters one of the approach sections, and signals for said tracks controlled by said traffic relays.

8. In combination, two intersecting rail-way tracks, a main section for each track extending in opposite directions from the point of intersection, an approach section for each track at each end of the main section, a normally open traffic relay for each track, means operating when a train moving toward the intersection enters an approach section to close the associated traffic relay provided the other traffic relay is open, and provided the main section of the track occupied by the train is clear, and signals for said tracks controlled by said traffic relays.

9. In combination, two intersecting rail-way tracks, a main section for each track extending in opposite directions from the point of intersection, an approach section for each track at each end of the main section, a normally open traffic relay for each track, means operating when a train moving toward the intersection enters an approach section to close the associated traffic relay provided the other traffic relay is open, two signals for each track for governing traffic in opposite directions through the main section of such track, and means for clearing each signal when a train approaches the signal provided the traffic relay for the track occupied by the train is closed and the other traffic relay is open.

10. In combination, two intersecting rail-way tracks, a main section for each track extending in opposite directions from the point of intersection, an approach section for each track at each end of the main section, a normally open traffic relay for each track, means operating when a train moving toward the intersection enters an approach section to close the associated traffic relay provided the other traffic relay is open, two signals for each track for governing traffic in opposite directions through the main section of such track, and means for clearing each signal provided the traffic relay for the track occupied by the train is closed and the other traffic relay is open, and the two signals for the other track are at stop.

11. In combination, two intersecting rail-way tracks, a main section for each track extending in opposite directions from the point of intersection, an approach section for each track at each end of the main section, a normally open traffic relay for each track, means operating when a train moving toward the intersection enters an approach section to close the associated traffic relay provided the other traffic relay is open, two signals for each track for governing traffic in opposite directions through the main section of such track, and means for clearing each signal when a train approaches the signal provided the traffic relay for the track occupied by the

train is closed and the other traffic relay is open, and provided the main section of the track occupied by the train is free.

12. In combination, two intersecting rail-way tracks, a main section for each track extending in opposite directions from the point of intersection, an approach section for each track at each end of the main section, a normally open traffic relay for each track, means operating when a train moving toward the intersection enters an approach section to close the associated traffic relay provided the other traffic relay is open, two signals for each track for governing traffic in opposite directions through the main section of such track, and means for clearing each signal when a train approaches the signal provided the traffic relay for the track occupied by the train is closed and the other traffic relay is open, and provided the two signals for the other track are at stop and the main section of the track occupied by the train is free.

13. In combination, two intersecting rail-way tracks, a main section for each track extending in opposite directions from the point of intersection, an approach section for each track at each end of the main section, a switch in the main section of the first track, a normally open traffic relay for each track, means operating when a train moving toward the intersection enters an approach section to close the associated traffic relay provided the other traffic relay is open, and the main section of the track occupied by the train is free, means for closing the traffic relay for the first track when said switch is reversed provided the main section of the first track is free, and signals for said tracks controlled by said relays.

14. In combination, two intersecting rail-way tracks, a normally open traffic relay for each track, one of which relays requires more time than the other to close its front contacts after energization, means operating when a train approaches the intersection on either track to close the associated traffic relay, means for preventing either traffic relay from closing if the other traffic relay is closed, and signals for said tracks controlled by said traffic relays.

15. In combination, two intersecting rail-way tracks, a main section for each track extending in opposite directions from the point of intersection, an approach section for each track, a normally open traffic relay for each track, means operating when a train moving toward the intersection enters the approach section to close the associated traffic relay provided the other traffic relay is open, and signals for said tracks controlled by said traffic relays.

In testimony whereof I affix my signature.

LESTER E. SPRAY.
